FIG. 1

FIG. 2

FIG. 3

FIG. 4

FIG. 5

FIG. 6

FIGURE 1 is a perspective view of the combination portable car console and arm rest showing my new design with the top closed;

FIGURE 2 is a similar perspective view showing the combination portable car console and arm rest with the top open;

FIGURE 3 is a side elevation;

FIGURE 4 is a front end elevation;

FIGURE 5 is a top plan view; and

FIGURE 6 is a vertical section on the line 6—6 of FIGURE 5 and in the direction of the arrows.

The characteristic features of my design reside in the curved ends of the side panels which extend forward beyond the cover, in combination with the handle disposed between said curved ends.

I claim:

The ornamental design for a combination portable car console and arm rest, as shown and described.
